CLAIM

We claim the ornamental design for modular storage unit, as shown and described.

DESCRIPTION

FIG. 1 is a front left perspective view of a modular storage unit according to an embodiment of the invention. The right side is a mirror image of the left side.

FIG. 2 is a front side elevational view of a modular storage unit according to an embodiment of the invention.

FIG. 3 is a rear side elevational view of a modular storage unit according to an embodiment of the invention.

FIG. 4 is a left side elevational view of a modular storage unit according to an embodiment of the invention. The right side is a mirror image of the left side.

FIG. 5 is a top view of a modular storage unit according to an embodiment of the invention.

FIG. 6 is a bottom view of a modular storage unit according to an embodiment of the invention; and,

FIG. 7 is a front left perspective view of a modular storage unit according to an embodiment of the invention. The right side is a mirror image of the left side.
